UNITED STATES PATENT OFFICE.

BENJAMIN HIRSCHHORN, OF NEW YORK, N. Y., ASSIGNOR TO NATIONAL URN BAG CO., OF NEW YORK, N. Y., A FIRM COMPOSED OF BENJAMIN HIRSCHHORN AND LOUIS HIRSCHHORN.

TEA-CARTRIDGE.

1,395,642.

Specification of Letters Patent.

Patented Nov. 1, 1921.

Application filed August 5, 1920: Serial No. 401,293.

To all whom it may concern:

Be it known that I, BENJAMIN HIRSCHHORN, a citizen of the United States, and a resident of the city of New York, in the 5 county of Bronx and State of New York, have invented certain new and useful Improvements in Tea-Cartridges, of which the following is a specification.

The present invention relates to a cartridge for percolating or extracting the flavor from tea-leaves or coffee. The invention pertains more particularly to that type of tea-cartridges, which is described in U. S. Letters Patent No. 1,310,796, granted 15 to me on July 22, 1919.

In the Letters Patent mentioned, a device for extracting essence from tea-leaves or coffee is described, comprising a bag of textile fabric, which contains a definite quantity 20 of tea-leaves or coffee, just sufficient for a single brewing. The mouth of this bag is drawn into folds, and closed by a metal strip, engaging and compressing said folds, thereby closing the mouth of said bag, said 25 strip attaching at the same time a suspending string to said bag.

The main object of the present invention is to so construct the inclosing metal strip, that it will, under all circumstances, keep 30 the suspending string in position upon the bag.

Another object of the invention is to utilize the metallic strip to hold in position 35 upon the bag a wrapper of paper or other material.

With these and other objects in view, which will more fully appear as the nature 40 of the invention is better understood, the same consists in the combination, arrangement and construction of parts hereinafter described, pointed out in the appended claims and illustrated in the accompanying drawings, it being understood that many changes may be made in the size and proportion 45 of the several parts and details of construction within the scope of the appended claims, without departing from the spirit or sacrificing any of the advantages of the invention.

One of the many possible embodiments 50 of the invention is illustrated in the accompanying drawings, in which:

Figure 1 is an elevation of a tea-cartridge constructed in accordance with the present invention; Fig. 2 is a section taken on line 55

2-2 of Fig. 1, on a larger scale; Fig. 3 is an elevation of the closing strip; and Fig. 4 is an elevation, partly in section, of the cartridge in its wrapper.

Referring now first to Figs. 1 to 3, inclusive, of the drawings, the numeral 10 indicates a bag of open-mesh textile fabric, such as for instance cotton, and of a size to contain just sufficient tea-leaves or coffee for a single brewing. This bag may be produced in any suitable manner, tea-leaves or coffee being placed thereinto after it has been properly sterilized. The mouth of the bag is closed by drawing or gathering the same into folds, and applying thereto a 60 metal strip 11, that is shaped to assume the form of a ring, embracing the folded portion of the bag below its mouth, thereby holding the folds under compression, so as to prevent escaping of the contents. The 65 strip 11 must, obviously, be made of non-corroding metal, or of a metal that is properly prepared to prevent corrosion. The ends of the metal strip are pointed or triangular, as shown at 12, and so arranged 70 in relation to each other that the small gap between the same runs in a plane that is disposed at an oblique angle to the longitudinal axis of the ring, as clearly appears from Figs. 1 and 2 of the drawings. The 75 purpose of this arrangement will appear 80 hereinafter.

For the purpose of facilitating the handling of the cartridge, there is secured thereto a flexible means, such as a string 13, to 85 which is attached at its free end a handle 14, made, for instance, of cardboard. This string serves also as the means for suspending the cartridge from the receptacle, such as a tea-pot or coffee-pot, in which the extraction is to take place. The string is secured to the cartridge by placing it against the folds around the mouth bag before the strip 11 is formed to constitute a ring. The strip 11 has thus a two-fold purpose, to wit: 90 First, it serves as a bag closure, and, second, it constitutes the means for attaching the handle carrying string to the bag. While the ends of the ring do not meet, as shown 95 in Figs. 1 and 3 of the drawings, the string 13 will under all circumstances be securely held in place, due to the fact that the gap between the ring ends extends, as above described, in a plane at an acute angle to the longitudinal axis of the ring. If the gap 100 105 110

were to extend parallel to the said longitudinal axis, the string could, in closing the bag, be placed in alinement with the said gap and would thus not be held in place. In the Letters Patent above referred to the ends of the ring overlap, in order to prevent the string from becoming loose, but in practice it has been found that the machine for forming and attaching rings of this type is rather 10 complicated.

If found desirable, a wrapper 15, preferably the form of a bag, (Fig. 4), may be held in place upon the bag by the ring 11. For this purpose, the filled bag is placed 15 into the wrapper and the mouth of the said wrapper simultaneously puckered with the mouth of the bag, the ring 11 being then applied, thereby holding the wrapper in position upon the securely closed bag. The 20 string 13 with its handle 14 is also held in position in the manner above referred to.

In brewing tea or coffee with the improved device, first the wrapper is removed therefrom, the cartridge being then taken hold 25 of by its handle 14 and lowered into the brewing receptacle, the free end of the string and handle being permitted to hang over the mouth of the receptacle, after which its cover is put in place. The cover will thus 30 hold the outer end of the string and handle

ready for further operation. Into the receptacle is poured a suitable quantity of boiling water, either before or after the insertion of the cartridge. When sufficient essence has been extracted from the tea leaves or coffee 35 within the cartridge, the cover of the brewing receptacle is removed and the bag withdrawn by grasping its handle 14. The wrapper 15 is provided in order to obtain a sanitary package.

40 What I claim is:—

A device for extracting essence from tea-leaves or coffee, comprising a bag of textile fabric having its mouth drawn into folds, a suspending string abutting with one of its 45 ends against said folds, and a metal strip encircling and compressing said folds for closing the mouth of said bag and for attaching said string thereto, the ends of said strip being spaced apart and the gap between said 50 ends being disposed at an oblique angle to a plane in which one of the flat faces of the encircling ring is located, thereby preventing said string from becoming disengaged from said bag.

55 Signed at New York, in the county of New York and State of New York this 25th day of June, A. D. 1920.

BENJAMIN HIRSCHHORN.
